UNITED STATES PATENT OFFICE.

CHARLES N. BARTON, OF INDIANAPOLIS, INDIANA.

CUTTING LINK FOR COAL-CUTTING CHAINS.

Application filed December 15, 1919. Serial No. 344,841.

To all whom it may concern:

Be it known that I, CHARLES N. BARTON, a citizen of the United States, residing at Indianapolis, in the county of Marion and State of Indiana, have invented a certain new and useful Improvement in Cutting Links for Coal-Cutting Chains, of which the following is a specification.

My invention relates to improvements in cutting links for coal cutting chains, and has for one object to provide new and improved means for locking the cutting bit into position in the bit carrying link of the chain. Another object is to provide means for locking the bit into position which will be immediately released when the holding pressure is released so that the bit itself may be readily withdrawn. Another object is to provide a single means for selectively tightening up and setting the bit holding wedge or releasing the wedge so as to permit free withdrawal of the bit.

My invention is illustrated more or less diagrammatically in accompanying drawings, wherein:

Figure 1 is a longitudinal sketch of a cutting bit link.

Figure 2 is a sketch along the line 2—2 of Figure 1.

Figure 3 is a side elevation.

Figure 4 is an end elevation of my improved form of locking wedge.

Like parts are indicated by like characters.

A is a bit holding link adapted to form a part of a coal cutting chain and will be pivoted in that chain by means of pivots A¹ A¹ which pass through open links of the chain A² A². Only occasional links of the chain are adapted to hold the cutting bit. The other links being merely ordinary block links like the base of the bit holding link alternating with open side links as shown.

The bit holding link has a hollow block B projecting laterally therefrom made up of a stirrup like part B¹ through which passes the cutting bit B².

B³ is a seat or chamber adjacent the stirrup B¹ adapted to contain a locking wedge B⁴. This locking wedge B⁴ is adapted to engage the under side of the bit B² and to be thrust thereagainst by the set screw B⁵ as it slides along the floor B⁶. This wedge is held loosely in the socket by a pin B⁷ which is free to slide in the latter slots B⁸, but

which holds the wedge against withdrawal from the seat.

The back end of the wedge is provided with an overhanging semicircular flange member C adapted to engage a groove C¹ in the end of the set screw, the relation of the parts being such that when the set screw is set in the wedge it is moved forward to clamp the bit and when the set screw is rotated in the opposite direction to draw it out, first the pressure on the wedge is released and then the enlarged end of the set screw engages the flange C and draws the wedge away from its locking position. This leaves the bit unsupported on its lower side so that it can drop down, be loosely held in the stirrup, and be easier disengaged.

The importance of this, is, that if the wedge is forced into place and then left there, coal dust and the like will be packed in about the wedge locking it in position and then when the operator comes to release the pressure on the wedge in the hope of withdrawal the bit will still be wedged or locked in place, and he will have to knock the bit loose. He would, of course prefer to knock the wedge loose and not knock on the delicate and expensive tempered bit, but the wedge is buried inside the link and the operator can do nothing but try to knock the bit loose. This is not necessary with my device, because, when the wedge itself is moved positively to the rear the bit also comes without difficulty.

It will be evident, while I have shown in the drawings an operative device, still many changes might be made both in shape and arrangement of parts without departing from the spirit of my invention, and I wish, therefore, that my drawings be taken in a sense diagrammatically.

I claim—

1. A bit holding link for coal cutting chains and the like comprising a link member adapted to be a part of a cutting chain, means for positively fastening the bit in position therein, comprising a bit engaging member and a set screw adapted to thrust it toward the bit, and a connection between the set screw and engaging member whereby withdrawal of the set screw moves the bit holding member away from the bit.

2. A bit holding link for coal cutting chains and the like comprising a link member adapted to be a part of a cutting chain,

means for rigidly fastening the bit in position therein, comprising a bit engaging member and a set screw adapted to thrust it toward the bit, and a connection between the set screw and engaging member whereby withdrawal of the set screw moves the bit holding member away from the bit, said connection comprising a groove about the end of the set screw and a flange on the bit engaging member adapted to penetrate said grooves.

3. A bit holding link for coal cutting chains and the like comprising a link member adapted to be a part of a cutting chain, means for rigidly fastening the bit in position therein, comprising a wedge, means for holding it against movement out of line with the line of action of the clamping means while permitting free movement along such line.

4. A bit holding link for coal cutting chains and the like comprising a link member adapted to be a part of a cutting chain, means for rigidly fastening the bit in position therein, comprising a bit engaging member, a set screw adapted to thrust it toward the bit, and a connection between the set screw and engaging member whereby withdrawal of the set screw moves the bit holding member away from the bit, the bit engaging member comprising a wedge, means for holding it against movement out of line with the line of action of the clamping means while permitting free movement along such line.

5. A bit holding link for coal cutting chains and the like comprising a link member adapted to be a part of a cutting chain, means for rigidly fastening the bit in position therein, comprising a bit engaging member, a set screw adapted to thrust it toward the bit, and a connection between the set screw and engaging member whereby withdrawal of the set screw moves the bit holding member away from the bit, said connection comprising a group about the end of the set screw and a flange on the bit engaging member adapted to penetrate said group, the bit engaging member comprising a wedge means for holding it against movement out of line with the line of action of the clamping means while permitting free movement along such line.

6. A bit holding link for coal cutting chains and the like comprising a link bit adapted to form a part of the chain, an open stirrup carried thereby, an abutment adjacent said stirrup, a link adapted to engage said stirrup at one side, a wedge adapted to engage the link at the other side, a set screw, screw threaded in said abutment and adapted to thrust the wedge against the bit, a groove about the end of the set screw, a flange projecting from the wedge penetrating said groove whereby retraction of

the set screw moves the wedge away from the bit and means for preventing movement of the wedge along any line except a line parallel with the axis of the set screw.

7. A bit holding link for coal cutting chains and the like comprising a link member adapted to be a part of a cutting chain, a bit receiving socket mounted thereon, means for positively fastening the bit in position therein, comprising a removable socket side member, a set screw adapted to thrust it toward the bit, and a connection between the set screw and the side member whereby withdrawal of the set screw draws the side member away from the bit and

8. A bit holding link for coal cutting chains and the like comprising a link member adapted to be a part of a cutting chain, said member being provided with a socket aperture adapted to receive a cutting bit and means for securing said bit in position in the socket, comprising a movable socket wall and positive means for forcing said socket wall directly against said bit and for withdrawing said socket wall from contact with said bit.

9. A bit holding link for coal cutting chains and the like comprising a link member adapted to be a part of a cutting chain, said member being provided with a socket aperture adapted to receive a cutting bit and means for securing said bit in position in the socket, comprising a movable socket wall and positive means for forcing said socket wall directly against said bit and for withdrawing said socket wall from contact with said bit, the axis of travel of said socket wall lying in the same vertical plane as the long axis of the bit.

10. A bit holding link for coal cutting chains and the like, comprising a link member adapted to be a part of the cutting chain, a bit receiving socket mounted thereupon, means for securing the bit in position therein, comprising a removable side wall for the socket and means for forcing it directly against the bit, along an axis lying in the same plane as the axis of the bit.

11. A bit holding link for coal cutting chains and the like, comprising a link member adapted to be a part of the cutting chain, a bit receiving socket mounted thereon, means for securing the bit in position therein, comprising a movable side wall for the socket and means for sliding it transversely away from the bit along a plane parallel with the bottom of the link.

12. A bit holding link for coal cutting chains and the like comprising a link member adapted to be a part of the cutting chain, a bit receiving socket mounted thereon, means for securing the bit in position therein, comprising a movable side wall for

the socket, and means for moving it transversely in relation to the bit.

13. A bit holding link for coal cutting chains and the like comprising a link member adapted to form part of a cutting chain, a fixed socket portion adapted to engage one corner of a bit of substantially square cross section, a socket member movable in relation thereto, adapted to engage an opposed corner of said bit, and positive means for moving it transversely in relation to said bit.

14. A bit holding link for coal cutting chains and the like comprising a link member adapted to form part of a cutting chain, a fixed socket portion adapted to engage

one corner of a bit of substantially square cross section, a socket member movable in relation thereto, adapted to engage an opposed corner of said bit, and positive means for moving it transversely in relation to said bit, said movable member comprising a block slideable along the bottom of the link, and provided with an inclined, grooved, bit engaging surface, the bit engaging surface of the fixed socket portion being inclined to over-hang and lie parallel with the inclined surface of said block.

Signed at Indianapolis, county of Marion and State of Indiana, this 4th day of December, 1919.

CHARLES N. BARTON.
